UNITED STATES PATENT OFFICE.

CHARLES AUSTEN PRESCOTT, OF VICTORIA, CANADA.

LATCH AND LOCK.

SPECIFICATION forming part of Letters Patent No. 790,659, dated May 23, 1905.

Application filed July 8, 1904. Serial No. 215,751.

To all whom it may concern:

Be it known that I, CHARLES AUSTEN PRESCOTT, a subject of the King of Great Britain, and a resident of Victoria, in the Province of 5 British Columbia and Dominion of Canada, have invented a new and Improved Door Latch and Lock, of which the following is a full, clear, and exact description.

This invention relates to insertable or mortise locks adapted to serve the dual purpose of a door lock and latch, and has for its objects to provide novel details of construction for a combined door lock and latch which are simple, compact, durable, and inexpensive 15 and that adapt the same for convenient application upon a door without requiring a large mortise to be made therein.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a transverse sectional view of a door in part and of the improved lock and latch, substantially on the line 1 1 in Fig. 2. Fig. 2 is a longitudinal sectional view of the 30 improvement mounted on a door, taken substantially on the line 2 2 in Fig. 1. Fig. 3 is a sectional plan view substantially on the line 3 3 in Fig. 1. Fig. 4 is an enlarged sectional side view of details of the lock and latch, 35 showing the lock-bolt thrown and details of the lock correspondingly adjusted. Fig. 5 is a sectional plan view of the lock mechanism, taken substantially on the line 5 5 in Fig. 4; and Fig. 6 is a detached perspective view of 40 a toothed hub-block employed as a detail of the latch mechanism.

The door-latch bolt 8 is preferably cylindrical in the body, of a suitable length, and formed with a beveled outer end 8^a, that is the 45 latching-nose of the bolt. From the opposite end of the latch-bolt 8 two rack-bars 9 project at opposite points in planes parallel with each other and with the longitudinal axis of said bolt. A cylindrical case 10, that is preferably formed of thin metal tubing, receives

the body of the latch-bolt 8, which is adapted to neatly slide therein; there being a radial flange 10^a formed or secured upon the end of the case 10 wherein the bolt 8 reciprocates, the flange 10^a being fixed upon a face-plate 55 10^b, which in service is secured upon the free edge of a door-stile A, as will hereinafter be further explained.

There is proper length given the case 10 to adapt it to receive other details of the latch 60 and also permit the latch-bolt 8 to freely reciprocate therein when given full throw for its locked adjustment or release and likewise for the reciprocation of the rack-bars 9. In the rear portions of the rack-bars 9 a series 65 of spaced slot-openings b is formed in each bar, these transversely-disposed slots leaving cross-bars c remain intact at their ends with the body of the flat bar they are formed in, said cross-bars c serving as rack-teeth. As shown, 70 three slots b are formed in each rack-bar 9, and the slots in one bar are arranged so that they do not lie directly opposite the slots in the other rack-bar, but somewhat nearer the flange 10^a, and, as appears in Figs. 2 and 4, 75 75 the slots in each rack-bar are widened toward the inner sides of said rack-bars by bevel-facing the sides of the rack-teeth c that are nearest the free inner ends of the rack-bars.

At a suitable point near the inner ends of 80 the rack-bars 9 a perforation is formed in the cylindrical wall of the case 10 at diametrically opposite points, and through this circular perforation d a square-bodied bar or spindle 11 is loosely passed, having a proper length to 85 pass through the door-stile A and receive the door-knobs 11^a, as will be more particularly described hereinafter.

Upon the spindle 11 a toothed hub 12 is mounted, which is positioned within the case 90 10 and by its engagement with the spindle 11 is held for rotation or rocking movement near the rear or inner ends of the rack-bars 9. A set of three teeth e project radially from the periphery of the hub 12, and these teeth are so 95 spaced apart and have such a length and relative positions forward of the axis of the hub and spindle 11 that when the spindle is rocked on its supports to be described in either direction the teeth will enter the slots b in the 100.

rack-bar toward which said teeth are turned and engage successively with the rear side of the rear slot and with the cross-bars or teeth *c*, thereby pulling the rack-bar and latch-bolt 8 rearward.

Upon the inner end of the latch-bolt 8 a diametrically-reduced bolt extension 8^b is formed or affixed centrally, which is of a length that will not interfere with the reciprocation 10 of the latch-bolt, and upon the extension 8^b an end portion of a coiled spring 13 is mounted.

Near the teeth *e* on the hub-block 12 an abutment-bar *g* is secured by its ends in the wall of the case 10 across its axis, and upon 15 the front side of the abutment-bar *g* the shoe *g'*, that is mounted upon the rear end of the spring 13, seats. The shoe *g'* is formed of a plate-metal strip bent into a rectangular loop, the flat transverse member *g*² of which engages the abutment-bar.

The diameter of the spring 13 and thickness of the spaced members of the shoe *g'*, that embrace the rear portion of said spring, is such that they together have lateral support 25 from the rack-bars 9 they are positioned between, so that the latch-bolt 8, which is normally pressed outward and has its nose 8^a projected exterior of the face-plate 10^b, may be pressed into the case 10 against stress of 30 the coiled spring 13 or be drawn therein, if the spindle 11 is rocked in either direction a sufficient degree to cause the teeth *e* to successively engage the cross-bars or teeth *c* that are on the rack-bar toward which the spindle 35 is rocked.

The door-locking mechanism, which is designed to coact with the door-latch that has been described, comprises the following details: A case for holding in proper relative 40 positions the working parts of the lock consists of two substantially similar half-sections 14, that are essentially L-shaped in cross-section and have contact at diagonally-opposite side edges, these case-sections being held together by a clamping-screw *h*. (Shown in Fig. 2.) The closing end walls 14^a of the case are curved into nearly semicircular form, as is indicated in Figs. 2 and 4, and, as shown in Fig. 1, two opposite side walls of the lock-case 45 are thickened in their normally upper portions, said side walls being parallel with each other, as shown at *i* in Fig. 5. Through the upper part of the lock-case a circular opening *k* is formed that is axially parallel with the sides *i* of the case and central between them, this opening receiving the inner end of the latch-bolt case 10, which projects a short distance therethrough, this engagement disposing the longitudinal axes of the cases in the same vertical 55 plane at right angles to each other. An abutment-block *i*' projects from one side wall *i* toward and nearly in contact with the other side wall *i* at a point which spaces it a proper distance from the normally lower end of the 60 lock-case. A tumbler-bar 15, having flat par-

allel sides, is pivoted near its normally upper end upon a side wall *i* of the lock-case near the case-wall 10, as shown at *l* in Figs. 2 and 4, and in the edge of the pendent tumbler-bar that hangs in loose contact with the inner vertical side wall of the abutment-block *i*' two spaced notches *m* are formed: Below the notches *m* the tumbler-bar 15 is reduced in thickness by removal of material, as at 15^a, thus affording clearance from the keyholes *n*, 75 that are formed oppositely in the case side walls *i*, as shown in Figs. 1, 2, and 4. A locking-bolt 16, that coacts with the bar 15 to lock the latch-bolt 8 from complete retraction, comprises an elongated slab of metal having such 80 thickness as permits it to slide loosely in the space between the tumbler-bar 15 and the opposite case side wall *i*, the edges of the locking-bolt near its center of length having a loose contact with the inner face of the abutment-block *i*' and the side wall of the case that is opposite to and parallel with said face, as is clearly shown in Figs. 2 and 5.

A locking-nose *o* on the slidable bolt 16 is positioned directly opposite and near to a suitable opening *o'*, that is formed in the side of the latch-bolt case 10 behind and near to the rear ends of the rack-bars 9.

Upon the side of the locking-bolt 16 that is in loose contact with the tumbler-bar 15 a 95 toe *m'* projects, which is adjacent to the abutment-block *i*' and is designed to enter either notch *m* to hold the locking-bolt in locked or unlocked adjustment.

There is a plate-spring 17 secured by one 100 end upon a side of the lock-case occupying space in the case behind the tumbler-bar 15, contacting with its free lower end upon the corresponding portion of said tumbler-bar, as shown in Figs. 2 and 4. There is a V-shaped 105 notch *p* formed in the edge of the locking-bolt 16 near its lower end, which permits a key *u* of proper form, that is passed into either keyhole *n*, to engage with either sloped edge 110 of the notch and slide the bolt, so that its nose *o* will be pressed into the hole *o'* or be withdrawn therefrom in accordance with the direction in which the key *u* (shown in dotted lines in Fig. 4) is turned.

It will be seen that if the nose *o* of the locking-bolt 16 has been introduced by a rotatable movement of the key *u* into the hole *o'* a turning movement of the key in the direction of the curved arrow in Fig. 4 will first impinge the key-bit upon the lower end 15^a of the 115 tumbler-bar 15 and rock said bar against pressure of the spring 17, which will carry the notch *m*, that is occupied by the toe *m'*, away from this toe, thus releasing the locking-bolt 16 from the tumbler-bar. A further rocking 120 movement of the key-bit *u* will cause it to impinge upon the lower inclined edge of the notch *p* and draw the locking-bolt 16 downward, thus withdrawing the nose *o* of said bolt from the bolt-hole *o'*, this unlocked ad- 130

justment of the bolt 16 appearing in Fig. 2. When the bolt 16 is moved downward far enough to release the nose o from the bolt-hole o' and the tumbler-bar 15 is permitted to 5 assume a normal pendent position, the lowered adjustment of the toe m' will permit its engagement within the lower notch m , thus securing the locking-bolt in unlocked condition.

To mount the improved latch and lock upon 10 a door that is represented at A in the drawings and which is a central portion of the vertical side member of a paneled door, a circularly-walled perforation r is formed in the edge of the door centrally and of a suitable 15 depth to permit the complete insertion of the case 10 therein, said perforation being counterbored at the outer end to produce a shallow recess wherein the radial flange 10^a and face-plate 10^b are embedded and secured by 20 screws s , as shown in Fig. 2. At a suitable point in one side of the door-stile A below the perforation r an open recess t is formed of a depth and marginal shape which will permit the case for the lock to be embedded at 25 the center of thickness of said stile, as appears in Fig. 1. Two escutcheon-plates 18 of suitable form and dimensions are provided as coverings for the recess or opening in the door, these plates being fixed in place by 30 screws or similar means. A keyhole u' is formed in each escutcheon-plate 18 opposite a respective keyhole u in the lock-case, so that an appropriate key may be inserted therethrough for operating the lock.

35 Concentric with the transverse perforation d in the latch-bolt case 10, in which the knob-spindle 11 is held to rock, a circular hole is formed in each escutcheon-plate 18, through which the spindle extends outward, and in 40 each of said holes a thimble 19 is secured that is loosely mounted upon the end of a shank 11^c of a door-knob 11^a, and, as shown in Fig. 1, said shanks are centrally perforated for the reception of the ends of the spindle 11, 45 said ends being held in place within the knobs by pins v , that pass through the knob-shanks and likewise through notches formed in the angular edge of the spindle, said pins being inserted through opposite perforations in the 50 thimble 19.

It will be seen that the manner of holding the knobs upon the spindle by an engagement of cross-pins in notched edges of the spindle is very advantageous, as it avoids boring holes 55 in the spindle, which weaken it, and also permits the use of a small spindle, which is desirable in the manufacture of locks of small size. It is claimed that the construction of the combined lock and latch enables it to be 60 applied upon doors of ordinary thickness without weakening the door-stile or marring it in any manner.

It will be seen in Fig. 2 that an opening o' is formed in the wall of the latch-bolt case 10 65 directly opposite the opening o therein, this

duplicate opening permitting a locked engagement of the locking-bolt nose o in either opening, so that the lock may be arranged for a door that swings to the right or left by simply turning the latch-bolt 10 and its case so 70 that an appropriate opening o' or o^2 will be adapted for reception of the nose o on the locking-bolt 16.

It is of course necessary that a suitable strike-plate 10^e be provided for a latching engagement of the nose 8^a on the latch-block 8 therewith, said strike-plate, which may be of any preferred shape, being secured upon the jamb of the door-casement A', toward which the door swings to close it. 80

It should be explained that as the nose of the locking-bolt 16 is projected within the latch-bolt case 10 at a point rearward of and near to either rack-bar 9 the rack-bar that is nearest to the nose o' when it is shot into the 85 case 10 will be prevented from sliding rearward sufficiently to release the latch-bolt nose 8^a from the strike-plate 10^e, so that the latch-bolt is also a locking-bolt.

As shown in Fig. 4, projections o^3 are formed 90 at the rear end of the tubular casing 10 and project toward each other and serve as abutments whereon the rear ends of the rack-bars 9 may impinge and prevent them from passing out of the rear end of the casing at any 95 time.

Having thus described my invention, I claim as new and desire to secure by Letters Patent—

1. The combination with a latch-bolt case, a latch-bolt slidable in the case and having a 100 reduced portion, and an abutment secured transversely in the case rearward of the latch-bolt, of a coiled spring mounted upon the reduced portion of the latch-bolt, and a plate-metal loop-bent shoe, mounted upon the rear 105 end of the spring and contacting with the abutment.

2. The combination with a latch-bolt case having a transverse perforation therein near its rear end, and a spring adapted to press the 110 bolt outward, of a knob-spindle held to rock in the transverse perforation, a toothed hub on the spindle, and two oppositely-arranged similar rack-bars rigidly secured to the latch-bolt and extending rearwardly therefrom, said bars 115 each having at its rear end transverse teeth formed thereon by transverse spaced slots, the slots of the bars being out of alinement, the teeth on the bars being respectively engaged with the teeth on the hub when the spindle is 120 rocked in opposite directions.

3. The combination of a latch-bolt case having a transverse perforation therein near its rear end, and an abutment in front of the perforation, a latch-bolt slidable in the casing, a 125 spring between the latch-bolt and the abutment of the case, a knob-spindle in the perforation of the case, a toothed hub on the spindle, and two oppositely-arranged rack-bars rigidly secured to the latch-bolt and pro- 130

vided at their rear ends with teeth, the teeth being formed by transverse openings in the bars, the openings of the bars being out of alinement and having their outer walls bevelled.

5 4. The combination with a latch-bolt case, and a perforated lock-case wherein an end of the latch-bolt case is inserted, of a spring-pressed tumbler-bar pivoted by one end and 10 hung pendent in the lock-case, said bar having two spaced notches in one side edge, and a slideable lock-bolt having notched lower end and a toe adapted to enter either notch of the tumbler-bar to hold the said bar in a locked 15 or unlocked position, the nose of the lock-bolt passing into a hole in the latch-bolt case when the lock-bolt is raised and locked in one of the notches.

20 5. The combination with a latch-case having an opening at its inner end, a latch-bolt in the said case, and a lock-case having one end perforated to receive the latch-case, of a spring-pressed tumbler-bar pivoted at one end and having its free end reduced, the said 25 bar being provided above the reduced end with two notches, and a sliding lock-bolt having a nose at one end to enter the opening of the latch-case behind the latch-bolt to prevent the latter from being retracted, a toe for engaging either of the notches of the tumbler-bar, and a notch at its lower end, opposite the reduced end of the tumbler-bar, as and for the 30 purpose set forth.

35 6. A door latch and lock, comprising a latch-case having an opening in one side at its inner end, a spring-pressed latch-bolt in the case

and having rearwardly-extending rack-bars rigid therewith, a knob-spindle mounted in the case, a toothed hub on the spindle, a lock-case having an opening at one end to receive 40 the latch-case, a pivoted and spring-pressed tumbler in the lock-case, a sliding bolt also in the lock-case and provided with a nose adapted to project into the latch-case in rear of one of the rack-bars of the latch-bolt, and an interlocking connection between the bolt and tumbler to hold the former in either position to which it is moved.

7. A door latch and lock, comprising a latch-case having an opening in one side at the inner 50 end, a spring-pressed latch-bolt in the case and having oppositely-arranged and rearwardly-extending bars, said bars being rigidly secured to the bolt and provided with openings forming teeth, a knob-spindle mounted 55 in the case, a toothed hub on the knob-spindle, a lock-case having an opening at one end through which the latch-case projects, a pivoted and spring-pressed tumbler in the lock-case, said tumbler having its free end reduced 60 and provided above its reduced end with spaced notches, and a sliding bolt in the lock-case and provided with V-shaped notch at its lower end and with a toe adapted to enter either of the notches of the tumbler. 65

In testimony whereof I have signed my name to this specification in the presence of two subscribing witnesses,

CHARLES AUSTEN PRESCOTT.
